UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

MEANS FOR TESTING STAYBOLTS FOR BOILERS.

1,323,030.

Specification of Letters Patent. Patented Nov. 25, 1919.

Application filed February 8, 1918. Serial No. 216,018.

To all whom it may concern:

Be it known that I, ETHAN I. DODDS, a citizen of the United States, and a resident of Pittsburgh, in the county of Allegheny and State of Pennsylvania, have invented 5 certain new and useful Improvements in Means for Testing Staybolts for Boilers; and I do hereby declare the following to be a full, clear, and exact description of the invention, such as will enable others skilled in the art to which it appertains to make and use the same.

This invention relates to improvements in means for testing staybolts for boilers,—one 15 object of the invention being to provide simple and efficient means which may be applied to staybolts while the same are in place in the steam boiler structure, for determining the integrity of the same.

20 A further object is to provide testing means which may be employed for determining whether the tell-tale hole of a stay-bolt contains moisture and thereby ascertaining whether the bolt is whole or fractured.

25 With these and other objects in view, the invention consists in certain novel features of construction and combinations of parts as hereinafter set forth and pointed out in 30 the claims.

35 In the accompanying drawings, Figure 1 is a sectional view; Fig. 2 is a rear end view of the testing device; Fig. 3 is a front end view; Fig. 4 is a view in side elevation, and Fig. 5 is a diagrammatical view showing the 40 testing device connected with an exhaust pump and a stay bolt.

1, 2 represent the outer and inner sheets which may form a water leg of a steam 45 boiler structure, said sheets being connected by flexible stay bolts, as is well understood. In the present instance, I have illustrated a stay bolt 3 which is threaded through the inner boiler sheet 2 and upset and at its 50 outer end, a rounded head 4 is provided,—said head having a bearing in a sleeve 5 threaded through the outer boiler sheet, and a cap 6 on said sleeve incloses the headed end of the bolt. The bolt 3 is also made with a tell-tale bore 7 which is accessible at its inner end for the application of my improved testing device and said tell-tale bore may be made to extend to and terminate within the headed end of the bolt.

55 My improved testing device comprises a

shell or casing 8, to the outer peripheral edge of which a packing ring 9 of rubber or other suitable material is secured, whereby the device may be caused to fit air-tight against the face of the inner boiler sheet 2, 60 as shown in Fig. 1. An annular head 10 is secured to the rear end of the casing 8 and made with a tubular extension 11 forming a nipple for the attachment of a suitable vacuum pump or a pipe leading to such 65 pump,—said tubular extension being caused to communicate with the chamber 12 formed by the shell or casing 8, through a port 13 in the rear end of the latter.

The shell 8 is provided therein with a 70 housing 14 (which may be cast integral therewith) for the accommodation of a nozzle 15,—the latter being made somewhat tapering at its free end to enter and closely fit the tapering inner end of the tell-tale 75 bore 7 of the bolt. A spring 16 located within the housing 14 serves to press the free end of the nozzle snugly into the tell-tale bore,—said spring bearing at one end 80 against the nozzle and at the other end 85 against a nut 17 screwed into the rear end of said housing. The nut 17 is made with a port 18 whereby the tube or nipple 11 may communicate, through the housing 14, with the nozzle 15 and with the tell-tale bore of 90 the bolt. The shell 8 is also provided therein with a passage 19 (the wall of which may be made integral with the shell 8 and housing 14) which communicates with the housing 14, and this passage receives a short pipe 95 20 which depends from the shell and carries an indicator cup 21 of glass or other transparent material.

In the operation of my improved testing means, the same is first applied to a bolt and 95 boiler sheet as clearly shown in Fig. 1. The pump will then be operated in a manner to exhaust the air from the chamber 12 and the tell-tale bore of the bolt. The exhausting of the air from the chamber 12 of the shell will 100 cause the latter to tightly hug (by suction) the boiler sheet 2 and the air will be exhausted from the tell-tale bore, through the nozzle 15, housing 14 and port 18. If the bolt is fractured so that moisture in the 105 form of water or condensed steam has entered the tell tale bore, the water will be withdrawn with the air by the action of the exhaust pump, and this water will pass through the nozzle 15 and gravitate from 110

the housing 14 through the passage 19 and pipe 20 to the indicator cup 21. Thus it will be seen that when the device is operated as above described, the presence of water in the cup 21 will at once indicate the fact that the bolt is fractured. On the other hand, if no water appears in the cup 21, this fact will denote that the bolt is whole. Thus the integrity of the bolt may be quickly, easily and accurately determined.

Various slight changes might be made in the details of construction of my invention without departing from the spirit thereof or limiting its scope and hence I do not wish to restrict myself to the precise details herein set forth.

Having fully described my invention, what I claim as new and desire to secure by Letters-Patent, is:—

- 20 1. Testing means for a stay bolt having a tell tale hole, said testing means comprising a portable device adapted to be applied to the open end of the bolt and having means for connection with suction means and means carried by said device, and located out of the path of movement of the air withdrawn from the bore of the stay bolt for collecting any water that may be drawn from the said tell tale bore.
- 25 2. A staybolt testing device comprising a portable suction device adapted to be applied to the end of the bolt, a nozzle with in said device adapted to communicate with the tell-tale hole in the bolt, and means also carried by said device for collecting any water that may be drawn out of the tell-tale bore.
- 30 3. A staybolt testing device, comprising a nozzle to communicate with the tell-tale bore of a stay bolt, means for connecting air exhausting means with said nozzle,

means for segregating water which may escape with the air, and a transparent container to receive such segregated water.

4. A staybolt testing device, comprising a shell for application to a boiler sheet, a nozzle carried by said shell for application to the tell-tale bore of a stay bolt, means for exhausting air from the chamber within said shell and through said nozzle, means for segregating water which may escape with the air from the tell-tale bore, and indicating means for collecting such segregated water.

5. A staybolt testing device comprising a shell open at one end, packing material on the peripheral edge of the open end of said shell, means for connecting the chamber within said shell with air exhausting means, a nozzle carried by said shell for connection with the tell-tale bore of a stay bolt, means for connecting said nozzle with the air exhausting means, an indicator container communicating with said nozzle to receive water which may escape through said nozzle from the tell tale bore.

6. A stay bolt testing device, comprising a shell having an open end for application to a boiler sheet, a housing within said shell, a spring-pressed nozzle carried by said shell for application to the tell-tale bore of a stay bolt, a transparent cup disposed under and communicating with said housing, and means connecting said housing with air exhausting means.

In testimony whereof, I have signed this specification in the presence of two subscribing witnesses.

ETHAN I. DODDS.
